DESIGN FOR A TALCUM-POWDER BOX.

54,604.

Specification for Design.

Patented Mar. 9, 1920.

Application filed June 28, 1916. Serial No. 106,532. Term of patent 7 years.

To all whom it may concern:

Be it known that I, HARRY R. COREY, a citizen of the United States, residing at Brooklyn, in the county of Kings and State of New York, have invented a new, original, and ornamental Design for a Talcum-Powder Box, of which the following is a specification, reference being had to the accompanying drawing, forming a part thereof.

On the drawing:

Figure 1 is a perspective view of a talcum powder box embodying my present invention;

Fig. 2 is a side elevation thereof; and

Fig. 3 is a top plan view.

The design is characterized by a body

which is regularly hexagonal in cross section and prismatic and parallel in shape from bottom to top, the said body being about two diameters in height. This body is surmounted by an arched top springing from a regularly hexagonal base plane and having thereon a cylindrical neck surmounted by an overhanging cap.

I claim:

The new, original, and ornamental design for a talcum powder box, as shown and described.

HARRY R. COREY.
